(57) **CLAIM**

The ornamental design for a toy car as shown and described.

DESCRIPTION

FIG. 1 is a perspective view of a toy car showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of area 9 shown in FIG. 1; and, FIG. 10 is an enlarged view of area 10 shown in FIG. 1.

The evenly spaced broken lines shown in the drawings depict portions of the toy car that form no part of the claimed design. The dot-dash-dot broken lines depict boundaries of the detailed enlargement that form no part of the claimed design.
